UNITED STATES PATENT OFFICE.

GEORGE R. STEERE, OF OWOSSO, MICHIGAN, ASSIGNOR TO STEERE ENGINEERING COMPANY, OF DETROIT, MICHIGAN, A CORPORATION OF MICHIGAN.

CHARGING MACHINE.

Application filed September 18, 1925. Serial No. 57,198.

It is the primary object of my invention to provide means, capable of automatic operation without the services of an operator, for charging a generator of a gas producing plant that can be operated at any cycle of the machine without shutting down the plant, thereby saving time and increasing the capacity of the plant, and reducing the amount of volatile loss.

10 It is a further object of my invention to provide a charging device that will supply weighed amounts of fuel at any desired time to the generator of a gas plant; reduce the amount of volatile loss and increase the efficiency of the machine by using small and frequent charges.

Another object of my invention is to provide an improved charger that will place fuel at any desired part or section of the 20 generator of a gas plant, thereby maintaining an even fuel bed, and preventing troubles now encountered due to inability to control the placing of fresh fuel.

A further object of my invention is to 25 provide an improved charging machine that can be quickly secured to or removed from a generator with the minimum loss of time.

With the above and other objects in view, 30 my invention consists in the arrangement, combination and construction of the various parts of my improved device, as described in the specification, claimed in my claims and shown in the accompanying drawings, in which:

35 Fig. 1 is an elevation showing more or less diagrammatically the top portion of a generator of a gas plant employing my invention, which is shown partly in section.

Fig. 2 is a plan view of my improved device.

Fig. 3 is a side elevation of my improved device as attached to a generator of a gas plant.

Fig. 4 is a detailed view of a part of my improved device.

Fig. 5 is a sectional view taken on lines 5—5 of Fig. 3.

Fig. 6 is a detail view of a part of my improved device.

50 I have shown the top portion 5 of a conventional type generator of a gas plant.

A conventional type carriage composed of the channel iron frame 20 secured together by plates 21 and a central cross channel 22 has axles 23 extending through one side 24

of the frame and through the central channel iron 22. Secured to these axles 23 are the car wheels 25 which are mounted on rails 26, and under the other side 27 of the carriage are supporting casters 28.

A magazine 29, supported on the carriage 19 by shoulders 30 resting on the side 24 and on the center channel iron 22, is placed over a nozzle 31 at the top of the generator 5. The magazine 29 is lowered from the carriage and fitted onto the nozzle 31 by lever arms 32 that are pivoted on the axles 23. One end 33 of these arms 32 is threaded onto a hand screw 34, which is fitted for rotation in a shackle 35 that is secured to a T plate 36 on the magazine 29 and the other end is divided into an upper lug 38 and a lower lug 39.

These lugs 38 and 39 are adapted to bear against lugs 40 on the side of the magazine, 75 so that when the hand screw 34 is turned in one direction, the lower lug 39 will bear against lug 40, thereby raising the magazine with the axle 23 as a pivot, and when the screw 34 is turned in the opposite direction, the upper lug 38 will press against lug 40, thus forcing the magazine downward and the axle 23 upward.

When the magazine is forced downwardly, the axle 23 is simultaneously lifted by the 85 force of the lugs 38 bearing upon the lug 40. The channel plates 22 and 24 have positioned on their underside, dogs 41 and the lifting of the axle 23 in turn raises the channel plates so that the dogs 41 are hooked under the projections in the nozzle 31, thus forcing a gas tight joint by increasing the weight bearing upon the top of the generator.

A fuel nozzle 43 having a cover seat 104 around the top edge thereof is suitably positioned on the magazine. Fastened to the side of the magazine adjacent the nozzle 43 is a hydraulic cylinder 44 with the piston shaft 45 that has the rack 46 secured thereto by means of the bracket 47 and the bolts 48. 100 A guideway 49 and roller brackets 50 having the rollers 51 therein are provided for the rack 46 on the cylinder 44.

On the fuel nozzle 43 are placed shaft supports 52, into which is fitted the shaft 53. 105 An arm 19 that has the nozzle cover 54 secured thereto, by means of bolt 55, and nut 56, is firmly fastened to the shaft 53. A supporting bracket 57 extends from the cylinder 44 to the end of the shaft 53. Posi-

tioned on the shaft 53 is a lever 58 that is pivotally connected at one end to an angle clin 59 placed on the rack 46 by a connecting link 60, and the pins 61. The other end 5 of this lever 58 is in turn pivotally joined to a lever 62 by the connection link 63 and the pins 64. The lever 62 is also secured to a protruding end of a shaft 65 that passes through a fuel container 66 that is pivoted 10 by a pin 67 to supports 68, extending up from the side 27 of the carriage frame.

The container 66 is provided with an open portion 69 and an enclosed chute end 70 leading therefrom. In the chute, secured to the 15 shaft 65 is a check gate 71. Mounted on the supports 68 and connected with the pin 67 is a scale that has the weight arm 72 with the weight platform 73.

An electric switch 74 is connected with the 20 arm 72 so that the power supplied by conventional type electric motor 105 for the conveyor 75 overhanging the container 66, can be automatically shut off when a predetermined weight is registered on the scale.

I also provide my improved device with 25 an automatic spreading means that can be turned to feed fuel to various sections of the generator 5. In the construction of this means, I mount a hydraulic cylinder 76 on the top of the magazine 29. This cylinder 76 is provided with a piston rod 77 that has the lower portion 78 extending down into the magazine 29 and the upper portion 79 extending through a stuffing box 80, with the 30 packing gland 100, and a ratchet casing 81 held by supports 82 secured to the cylinder 76. Loosely positioned around the rod 77, 35 is a collar 83, to which is secured a hand lever 84 that has a protruding end 85. A sprocket gear 86 is keyed to the rod 77 just 40 below the ratchet casing 81, and secured on the inside of the ratchet casing 81 is a pawl 87, which meshes with a ratchet gear 88 that has an inside pin 89 projecting into a spiral 45 groove 90 in the rod 77.

Thus it will be seen that the rod 77 may be raised or lowered by the hydraulic cylinder 76 the distance between the stuffing box 80 and the casing 81. On the down stroke, 50 the pin 89 in the groove 90 turns the ratchet gear 88 on the pawl 87, thus maintaining a given position for the rod 77. On the return stroke, the pawl 87 sets in one of the teeth of the ratchet, making the same stationary 55 and the rod 77 is then partially rotated by the spiral groove 90 following around the stationary pin 89.

It will be further noted, if it is desired to 60 turn the rod 77 to any particular point when the same is lowered, the pawl 87 is raised out of the ratchet gear 88 and the hand lever 84 is then raised horizontally so that the end 85 thereof will set between the teeth of the gear 86. Thus, the rod 77 can be turned to 65 any point between the supports 82. When

the point wanted is beyond the supports 82, the lever 84 is lowered until the end 85 is free from the gear 86 and then turned back on the collar 83 to the opposite support 82, at which point the first action is repeated.

The lower portion 78 of the rod 77 is held in position by a bearing 91 supported by cross beams 92, secured to the inside facing of the magazine. Placed on the end of this portion 78 is a spreader 93 that has an outwardly beveled bottom 94. This bottom 94, when the spreader is in closed position, wedges against a shoulder 95 on the inside of the magazine 29, making a gas tight joint, and at the same time leaves the spreader 93 clear of the generator top and nozzle 31, so that the charger may be moved on the carriage. The spreader 93 has a slanted face 96 extending diagonally from a top edge 97 to the top edge of the bottom 94. On the extreme end of the upper portion 79 of the rod 77 is a block 98 having an indicating arrow 99 showing the exact position of the spreader 93.

In practical operation, my improved device is placed over the generator 5 of a gas plant, lowered on and then secured to the nozzle 31 by the lever arm 32 operated with the hand screw 34, and the dogs 41. The container 66, which is placed in a horizontal position and has the gate 71 raised, is then filled with fuel from the conveyor 75 until a predetermined weight is registered on the scale, at which time the electric switch 74 automatically shuts off the power and stops the conveyor. The hydraulic cylinder 44 is then set in operation so that the lever 58 partially rotates the shaft 53 to lift the cover 54 and at the same time the container 66 is tilted on the pin 67 by the connection link 63 and the lever 62. The leverage and the working of the hydraulic cylinder 44 are so arranged that the cover 54 will be completely raised and the container tilted, having the chute 70 adjacent the fuel nozzle opening, without interfering with each other. After the container 66 is completely lowered, the lever 62 is brought down opening the gate 71, thus allowing the fuel to pass through the chute 70 and fuel nozzle 43, into the magazine 29. After fuel is placed in the magazine the container 66 and the cover 54 are again placed in their original positions by reverse movement of the rack and leverage.

The spreader 93 is then lowered by the hydraulic cylinder 76 and the slanted face 96 places the fuel over a limited area in the generator 5. When the spreader is raised, the same will be turned by the groove 90, the pin 89, pawl 87 and the ratchet 88 so that a different section of the generator may be charged on the next down stroke of the spreader. This is repeated until fuel is evenly distributed over the entire generator surface.

If fuel is desired at any particular point, the pawl 87 is lifted out of the ratchet 88, the rod 77 lowered, and then the hand lever 84 is used as aforementioned.

5 It is obvious that various changes may be made in the arrangement, combination and construction of the various parts of my improved device without departing from the spirit of my invention, and it is my intention 10 to cover by my claims such changes as may be included within the scope thereof.

What I claim is:

1. In combination with a generator of a gas plant, a carriage, a magazine mounted thereon and removably secured to said generator, a fuel container, means for supplying fuel to said container and means for feeding fuel to said magazine from said container.

20 2. In combination with a generator of a gas plant, a carriage, a magazine mounted thereon and removably secured to said generator, means for supplying said magazine with fuel and means for charging fuel to different portions of said generator from said magazine.

30 3. In combination with a generator of a gas plant, a carriage, a magazine mounted thereon and removably secured to said generator, a fuel container, means for supplying fuel to said magazine from said container, a spreader adapted to fit into said magazine and means for lowering said spreader to charge said generator with fuel from the magazine.

40 4. In combination with a generator of a gas plant, a carriage, a magazine mounted thereon and removably secured to said generator, a fuel container, a fuel conveyor for supplying fuel to said container, means for loading fuel into said magazine from said container, a spreader adapted to fit into said magazine and means for lowering said spreader to charge said generator with fuel from the magazine.

50 5. In combination, a carriage, a magazine mounted thereon, a fuel container, a conveyor for supplying fuel to said container, means for weighing the fuel in said container, and means for feeding fuel into said magazine from said container.

60 6. A charger for a gas generator comprising a magazine mounted on the outside of the generator, means for loading the magazine with fuel, means for dumping the fuel from the magazine into the generator comprising a fuel directing element adapted to be lowered into the generator to deposit the fuel from the magazine at localized points around the generator and means for raising the element to reload the magazine.

65 7. A charger comprising a carriage, a magazine mounted thereon, a fuel nozzle having a gas tight cover therefor extending up from said magazine, means for opening

and closing said cover and means for loading said magazine with fuel through said nozzle.

8. A charger for a gas generator comprising a magazine mounted on the outside 70 of the generator, means for loading the magazine with fuel, means for dumping the fuel from the magazine into the generator comprising a fuel directing element adapted to be lowered into the generator to deposit 75 the fuel from the magazine at localized points around the generator, means for raising the element to reload the magazine and means for automatically turning the element as the magazine is emptied and re-loaded. 80

9. A charger comprising a carriage, a magazine, mounted thereon, a fuel nozzle extending from said magazine, a fuel container having a chute end leading therefrom, a gate in said chute adapted to close 85 the same and means for opening said gate and loading said magazine with fuel from said container through said nozzle.

10. A charger comprising a carriage, a magazine mounted thereon, means for raising and lowering said magazine from and on said carriage, a fuel nozzle extending from said magazine, a fuel container, means for loading said magazine with fuel from said container through said nozzle and means for 90 feeding the fuel from said magazine. 95

11. A charger comprising a carriage, a magazine mounted thereon, a fuel nozzle extending up from said magazine and a gas tight cover for said nozzle, a fuel container having a chute end leading therefrom, a gate in said chute adapted to close the same and means for simultaneously opening said cover, tilting said container so that the chute end will be adjacent said nozzle and opening said gate, thereby permitting fuel to pass from said container through said nozzle into said magazine. 105

12. A charger comprising a carriage, a magazine, mounted thereon, a fuel nozzle extending up from said magazine and a gas tight cover for said nozzle, a fuel container having a chute end leading therefrom, a gate in said chute adapted to close the same, a hydraulic cylinder secured to the side of 110 said nozzle and means operated by said cylinder for simultaneously opening said cover, tilting said container so that the chute end will be adjacent said nozzle and opening said gate, thereby permitting fuel to pass from said container through said nozzle into said magazine. 115

13. In combination, a carriage, a magazine mounted thereon, a fuel nozzle extending up from said magazine, shaft supports on said nozzle having a shaft positioned therein, a gas tight cover for said nozzle secured to said shaft, a hydraulic cylinder, a piston rod extending from both ends of said cylinder, means for reciprocating said 120 125 130

rod in said cylinder, a rack placed on said piston rod, a fuel container having a chute end, a gate in said chute and means connecting said shaft, gate and rack, whereby said cover can be moved simultaneously with the tilting of said container and the opening of said gate by said piston rod.

14. In combination, a carriage, a magazine mounted thereon, a fuel nozzle extending up from said magazine, shaft supports on said nozzle, a shaft positioned therein, a gas tight cover for said nozzle secured to said shaft, a lever fulcrumed on said shaft, a fuel container having a chute end, a gate in said chute, means connecting said gate with one end of said lever, a hydraulic cylinder positioned on said nozzle, a piston rod extending from both ends of said cylinder, means for reciprocating said rod in said cylinder, a rack placed on said piston rod and means connecting said rack with the other end of said lever so that reciprocation of said piston rod will cause simultaneous movement of said cover and container and delayed movement of said gate.

15. In combination, a carriage, a magazine mounted thereon, means for feeding a predetermined amount of fuel to said magazine, a hydraulic cylinder secured to the top of said magazine, a piston rod extending down into said magazine from said cylinder and a spreader secured to the end of said rod adapted to form a gas tight bottom for said magazine.

16. A construction as set forth in claim 15 wherein a shoulder is placed around the inside of said magazine adjacent the bottom thereof and the bottom of said spreader is beveled to form a gas tight joint when in closed position.

17. In combination, a carriage, a magazine mounted thereon, means for supplying said magazine with fuel, a hydraulic cylinder secured to the top of said magazine, a casing supported above said cylinder, a piston rod in said cylinder having the lower end extending down into said magazine and the upper end through said casing, means for reciprocating said piston rod in said cylinder, and means in said casing for partially rotating said rod.

18. In combination, a carriage, a magazine mounted thereon, means for supplying said magazine with fuel, a hydraulic cylinder secured to the top of said magazine, a casing supported above said cylinder, a piston rod in said cylinder having the lower end extending down into said magazine and the upper portion through said casing, a spreader secured to the lower end of said rod and adapted to form a gas tight bottom for said magazine, when in closed position, means for reciprocating said piston rod in said cylinder and means in said casing for partially rotating said rod on each com-

plete stroke, thereby changing the position of said spreader.

19. In combination, a carriage, a magazine mounted thereon, means for supplying said magazine with fuel, a hydraulic cylinder secured to the top of said magazine, a casing supported above said cylinder, a piston rod in said cylinder having the lower end extending down into said magazine and the upper portion through said casing, a spreader secured to the lower end of said rod and adapted to form a gas tight bottom for said magazine when in closed position, means for reciprocating said piston rod in said cylinder, a spiral groove in the upper portion of said rod, a ratchet gear having an inside pin, projecting into said groove, fixed for rotation in said casing and a pawl adapted to allow free movement of said ratchet on the downstroke of said rod and to become set in the teeth of said ratchet on the up stroke, thereby partially rotating the rod to change the position of said spreader.

20. In combination, a carriage, a magazine mounted thereon, means for supplying said magazine with fuel, a hydraulic cylinder secured to the top of said magazine, a casing supported above said cylinder, a piston rod in said cylinder having the lower end extending down into said magazine and the upper portion through said casing, means for reciprocating said piston rod in said cylinder and means for turning said rod, consisting of a gear keyed to said rod below said casing, a collar loosely positioned on the rod adjacent said cylinder, a hand lever pivoted to said collar and a projecting end on said hand lever adapted to be inserted between the teeth of said gear when the rod is at the end of its down stroke, by raising said hand lever to a horizontal position.

21. In combination, a carriage, a magazine mounted thereon, means for supplying said magazine with fuel, a hydraulic cylinder secured to the top of said magazine, a casing supported above said cylinder, a piston rod in said cylinder, having the lower end extending down into said magazine and the upper portion through said casing, a spreader secured to the lower end of said rod, means for reciprocating said piston rod in said cylinder, means for turning said rod and spreader, consisting of a gear keyed to said rod below said casing, a collar loosely positioned around said rod adjacent said cylinder, a hand lever pivoted to said collar and a projecting end on said hand lever adapted to be inserted between the teeth of said gear when the rod is at the end of its down stroke by raising said hand lever to a horizontal position and automatic means in said casing for partially rotating said rod on each complete stroke thereby changing the position of said spreader.

GEORGE R. STEERE.
